US0D1062723S

(12) **United States Design Patent** (10) Patent No.: **US D1,062,723 S**
(45) Date of Patent: ** Feb. 18, 2025

(54) **TABLET COMPUTER**

(71) Applicant: **JRD COMMUNICATION (SHENZHEN) LTD.**, Guangdong (CN)

(72) Inventors: **Zhongrong Zeng**, Guangdong (CN); **Yifeng Feng**, Guangdong (CN); **Qibin Qi**, Guangdong (CN)

(73) Assignee: **JRD COMMUNICATION (SHENZHEN) LTD.**, Guangdong (CN)

(**) Term: **15 Years**

(21) Appl. No.: **35/519,980**

(22) Filed: **Dec. 20, 2023**

(80) **Hague Agreement Data**

Int. Filing Date: **Dec. 20, 2023**

Int. Reg. No.: **DM/234832**

Int. Reg. Date: **Dec. 20, 2023**

Int. Reg. Pub. Date: **Feb. 9, 2024**

(30) **Foreign Application Priority Data**

Sep. 20, 2023 (CN) 202330614377.6

(51) **LOC (15) Cl.** **14-02**
